CLAIM

The ornamental design for a brush head, as shown and described.

DESCRIPTION

FIG. 1 is a perspective view of a brush head, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear, top, and right side perspective view thereof; and,

FIG. 9 is an enlarged view of the portion labeled "9" encircled in FIG. 1.

1 Claim, 9 Drawing Sheets(56)
